UNITED STATES PATENT OFFICE.

JOHN W. THOMAS, OF KANSAS CITY, KANSAS, ASSIGNOR OF ONE-HALF TO JOHN R. HAMILL, OF KANSAS CITY, MISSOURI.

RAILWAY-TRACK APPLIANCE.

1,149,307.

Specification of Letters Patent. Patented Aug. 10, 1915.

Application filed December 17, 1913. Serial No. 807,272.

To all whom it may concern:

Be it known that I, JOHN W. THOMAS, a citizen of the United States, residing at Kansas City, in the county of Wyandotte and State of Kansas, have invented certain new and useful Improvements in Railway-Track Appliances, of which the following is a specification.

My invention relates to improvements in railway track appliances, and my object is to provide a simple device of this character especially adapted to preventing main and guard rails from tipping when subjected to heavy lateral pressure such as is exerted thereon by a train rounding a curve.

In order that the invention may be fully understood, reference will now be made to the accompanying drawing, in which:

Figure 1 is a perspective view of my appliance. Fig. 2 is a plan view of the appliance with main and guard rails in position thereon. Fig. 3 is an end view of the appliance with main and guard rails in position thereon. Fig. 4 is a modified form of the appliance with guard and main rails in position thereon.

In said drawing, A designates a cross-tie, B a main rail, and C a guard rail, all of usual type, except that part of the guard rail base adjacent to the main rail is removed as clearly shown on Fig. 3, to bring the balls of the rails in proper relation to each other.

1 designates my appliance which embodies a tie-plate member 2, adapted to be secured upon the underlying cross-tie in the customary manner by driving spikes C through holes 3, 4, and 5. The under side of member 2 is provided with teeth 6, which become embedded in the tie and thus prevent the appliance from moving longitudinally of said tie.

Member 2 is provided at its ends with extensions 7 and 8, having abutments 9 and 10 inclined upwardly and toward each other and provided with angular seats 11 and 12, to receive the adjacent corners of the balls of the rails B and C, respectively. Member 2 is provided at its upper side adjacent the bases of the abutments with flanges 13-14 having beveled upper surfaces 15-16, respectively, said flanges being provided to engage the adjacent margins of the rail bases to prevent the same from moving laterally in the direction of said flanges.

17 designates a T-shaped retaining member on the tie-plate member 2, at a point intermediate the flanges 13-14 to engage and overlap the adjacent margins of the rail bases, as shown clearly on Fig. 3.

The abutments 9 and 10 are arranged at such an angle and so curved at their inner lower portions as to permit the outer margins of the rail bases to be tilted upward to allow the inner margins of said bases to be inserted beneath the retaining member 17, and the seats 11 and 12 are so disposed with relation to said retaining member 17, the upper surface of the tie-plate member 2, and the flanges 13 and 14, as to receive the balls of the rails B and C, respectively, when said rails are rocked into the respective positions disclosed by Fig. 3.

In practice, the appliance is firmly secured to a tie by driving spikes through the holes 3. The adjacent margins of the rail bases are then inserted beneath the oppositely-disposed overlapping portions of the retaining member 17 with the opposite sides of their bases resting upon the beveled surfaces 15-16 of the flanges 13-14, respectively. Pressure is then applied upon the rails until they slip down from the beveled surfaces 15-16 and become securely seated upon the member 2. As the rails become seated their balls rock into their respective seats 11-12 in the abutments 9-10, which reliably secure the rails from tipping when subjected to heavy lateral pressure.

Spikes are then driven through the holes 4-5 to engage and overlap the outer margins of the rail bases, the inner margins of which are reliably secured by the T-shaped retaining member 17. In some instances, it is desirable to set the guard rail higher than the main rail to prevent the wheel flanges of a train from climbing said guard rail, so I have provided a modified form disclosed by Fig. 4, in which the tie-plate member 2^a has a low seat 18 for the main rail B' and a high seat 19 for the guard rail C'. In other respects this modified form is substantially the same as the preferred form above described.

Having thus described my invention, what I claim and desire to secure by Letters Patent is:

A device of the character described, consisting of a tie-plate member adapted to be interposed between a cross tie and two rails,

flanges on said member to abut against the outer margins of the rail bases, a T-shaped member on the tie-plate member intermediate said flanges and adapted to overlap 5 the inner or adjacent margins of the rail bases, and two abutments extending upwardly from opposite ends of said tie-plate member and provided at their upper ends with seats, said abutments being arranged at such an angle and so disposed with relation to the flanges, the T-shaped member,

and the upper surface of the tie-plate member as to receive the balls of the rails when the latter are rocked into their respective positions upon the tie-plate member, substantially as shown and described. 15

In testimony whereof I affix my signature, in the presence of two witnesses.

JOHN W. THOMAS.

Witnesses:

F. G. FISCHER,
T. C. FISCHER.
